(57) **CLAIM**

The ornamental design for a curved screen protector for an electronic device, as shown and described.

DESCRIPTION

FIG. 1 is a perspective view of an embodiment showing the new design for a curved screen protector for an electronic device;

FIG. 2 is a plan view of a top edge and bottom edge of the curved screen protector of FIG. 1;

FIG. 3 is a plan view of a front surface of the curved screen protector of FIG. 1;

FIG. 4 is a plan view of a left-side edge and right-side edge of the curved screen protector of FIG. 1;

FIG. 5 is a plan view of a back surface of the curved screen protector of FIG. 1;

FIG. 6 is a perspective view of another embodiment of the curved screen protector for an electronic device;

FIG. 7 is a plan view of a top edge and bottom edge of the curved screen protector of FIG. 6;

FIG. 8 is a plan view of a front surface of the curved screen protector of FIG. 6;

FIG. 9 is a plan view of a left-side edge and right-side edge of the curved screen protector of FIG. 6;

FIG. 10 is a plan view of a back surface of the curved screen protector of FIG. 6;

FIG. 11 is a perspective view of another embodiment of the curved screen protector for an electronic device;

FIG. 12 is a plan view of a top edge and bottom edge of the curved screen protector of FIG. 11;

FIG. 13 is a plan view of a front surface of the curved screen protector of FIG. 11;

FIG. 14 is a plan view of a left-side edge and right-side edge of the curved screen protector of FIG. 11; and,

FIG. 15 is a plan view of a back surface of the curved screen protector of FIG. 1.

The broken lines in the drawings depict environmental subject matter/or parts of curved screen protector for an electronic device and form no part of the claimed design.
